UNITED STATES PATENT OFFICE.

GEORGE S. LEE, OF HAWTHORNE, NEW JERSEY, ASSIGNOR TO WHEEL
WITHIN WHEEL COMPANY, OF NEW YORK, N. Y., A CORPORATION
OF NEW JERSEY.

VEHICLE-WHEEL.

SPECIFICATION forming part of Letters Patent No. 700,515, dated May 20, 1902.

Application filed December 6, 1901. Serial No. 84,917. (No model.)

To all whom it may concern:

Be it known that I, GEORGE S. LEE, a citizen of the United States of America, residing at Hawthorne, county of Passaic, State of New Jersey, have invented certain new and useful Improvements in Vehicle-Wheels, of which the following is a specification, reference being had to the accompanying drawings, forming a part thereof.

10 My invention relates to vehicle-wheels, and particularly to vehicle-wheels of the type described and claimed in United States Letters Patent No. 672,908 of April 30, 1901. The improvements herein particularly relate to 15 the construction of the hub member of the wheel, and more particularly to the construction of the hub proper.

The object of the present invention is to simplify and improve the construction and 20 arrangement of parts in the type of wheel set forth in such patent and to strengthen the wheel, so that it may be applicable to a heavy class of work.

I will now proceed to describe a vehicle- 25 wheel embodying my invention and will then point out the novel features in claims.

In the drawings, Figure 1 is a view in side elevation of a vehicle-wheel embodying my invention. Fig. 2 is a view in central transverse section of the same, the plane of section being taken upon the line 2-2 of Fig. 1. Fig. 3 is a similar view in central transverse section, the plane of section being taken upon the line 3-3 of Fig. 1. Fig. 4 is an enlarged 35 perspective view in detail of the floating plate employed. Fig. 5 is a similar detail view in perspective of one of the intermediate guide-plates employed. Fig. 6 is a detail face view of one of the hub-sections.

40 My improved wheel comprises two members, one carrying the hub portion, and which, as heretofore, I designate the "hub" member, and the other carrying the outer rim or tire, and which I term the "tire" member.

45 The hub member comprises the hub proper, herein designated as a whole by the reference character 1, a plurality of spokes 2 radiating therefrom, and a rim 3. The tire member comprises a tire-rim 4, a plurality of spokes 5, and a floating plate 6. The floating plate

is provided with a slot or slots 7, and the hub is provided with similar slots or grooves 8 at right angles thereto. Intermediate guide-plates 9, of which one is shown in detail in Fig. 5, are provided and are arranged between the opposite faces of the floating plate and the inner faces of the hub. The intermediate guide-plates are each provided with tongues 10, projecting therefrom upon opposites thereof and at right angles to each other. 55 These tongues are fitted to the grooves or slots 7, 8, and the said guide-plates will therefore positively lock the hub and the floating plate against relative rotation of each other, but will permit relative movement of the two 60 members in the plane of rotation of the wheel. 65

An annular cushioning device, herein shown as a flexible inflatable tube 11, is arranged between the rim 3 of the hub member and the tire-rim 4. A supporting-rim 12 is 70 preferably secured to the tire-rim 4 to form a convenient support for the said cushioning device.

The hub proper, 1, comprises two separable and separate sections. One of these sections 75 is provided with a central projection 13 and the other with an orifice 14, adapted to receive the projection 13. The projection 13 has a shouldered portion comprising two ears 15, which fit into corresponding recesses 80 16 in the orifice 14 of the other section.

A nut 17 is fitted to the projection 13 of the one hub-section and engages the other hub-section. When the said nut is tightened up, the ears 15, comprising the shouldered portion of the projection 13, are brought up against the inner walls of the recesses 16 and the two hub-sections are firmly locked together. The ears 15 upon the one hub-section comprise a portion which is eccentric of the 85 axis of the hub and fitting into corresponding recesses in the other hub-section lock the two hub-sections against relative rotation with respect to each other.

The foregoing construction provides a sectional hub in which the outer periphery thereof may be substantially cylindrical and of smaller diameter than the floating plate supported therein, and hence in which there are no exposed pockets for dust to accumulate. 90 100

In this construction it is practically impossible for dust to enter into the interior of the hub, for the motion of the floating plate within the hub tends rather to work the dust outwardly than inwardly. Further, it is very much easier to keep this style of hub clean than the hub in which certain portions thereof extend beyond the outer periphery of the floating plate for the purpose of being secured together by bolts connecting such portions over the edge of the floating plate.

The spokes 2 of the hub member are arranged in pairs, and the spokes of each pair converge from the opposite hub-sections to the said rim 3. The spokes are all straight-line spokes, and by such arrangement and construction great strength and rigidity are provided. It will also be noted that the severe side strain to which a wheel of this character is often subjected is particularly well resisted.

The tire member spokes 5 are disposed alternately of each pair of spokes 2, and the said spokes 5 surround the cushioning-tube 11, leaving a sufficient space to allow free play backward and forward for the two members.

The spokes 5 are preferably made with detachable portions, such as the caps 18, in order that ready access may be had to the cushioning device 11.

I do not desire to be limited only to the precise details of construction and combination of parts as herein set forth, as the same may obviously be varied within wide limits without departing from the spirit and scope of my invention.

What I claim is—

1. A wheel comprising two relatively movable members, one a tire member and the other a hub member, and having a cushioning device between them, the hub member comprising two hub-sections, a plurality of spokes, and a rim, one of said hub-sections provided with a central orifice adapted to receive a projection upon the other hub-section, and the said other section provided with a central projection adapted to pass through said orifice; and a locking device between the first said hub-section and the projection of the other said hub-section.

2. A wheel comprising two relatively movable members, one a tire member and the other a hub member, and having a cushioning device between them, the hub member comprising two hub-sections, a plurality of spokes, and a rim, one of said hub-sections provided with a central orifice adapted to receive a projection upon the other hub-section, and the said other section provided with a central projection adapted to pass through said orifice; and a nut mounted upon the projection of the one section, and engaging the other said section.

3. A wheel comprising two relatively movable members, one a tire member and the other a hub member, and having a cushioning device between them, the hub member comprising

two hub-sections, a plurality of spokes, and a rim, one of said hub-sections provided with a central orifice adapted to receive a projection upon the other hub-section, and the said other section provided with a central projection adapted to pass through said orifice, said central projection having a portion eccentric of the axis of the hub, whereby the two hub-sections are held together against relative rotation; and means whereby the said sections are held together against relative movement longitudinally of their axis of rotation.

4. A wheel comprising two relatively movable members, one a tire member and the other a hub member, and having a cushioning device between them, the hub member comprising two hub-sections, a plurality of spokes, and a rim, one of said hub-sections provided with a central orifice adapted to receive a projection upon the other hub-section, and the said other section provided with a central projection adapted to pass through said orifice; said central projection having a portion eccentric of the axis of the hub, whereby the two hub-sections are held together against relative rotation; and a nut mounted upon the projection of the one section and engaging the other said section.

5. A wheel comprising two relatively movable members, one a tire member and the other a hub member, and having a cushioning device between them, the hub member comprising two hub-sections, a plurality of spokes, and a rim, one of said hub-sections provided with a central projection adapted to pass through an orifice in the other section, and having a shouldered portion, and the said other section provided with a central orifice to receive such shouldered projection, and a nut mounted upon the projection of the one section, and engaging the other said section.

6. A wheel comprising two relatively movable members, one a tire member and the other a hub member, and having a cushioning device between them, the hub member comprising two hub-sections, a plurality of spokes, and a rim, one of said hub-sections provided with a central projection adapted to pass through an orifice in the other section, and having a shouldered portion eccentric of the axis of the hub, and the said other section provided with a central orifice to receive such projection, and recessed to receive the eccentric shouldered portion thereof, and a nut, mounted upon the projection of the one section, and engaging the other said section.

7. A wheel comprising two relatively movable members, one a tire member and the other a hub member, and having a cushioning device between them, the hub member comprising two hub-sections, a plurality of spokes, and a rim, one of said hub-sections provided with a central projection adapted to pass through an orifice in the other section, and having two projecting ears, and the said other section provided with a central orifice to re-

ceive such projection and having recesses to receive the said ears, and a nut mounted on the projection of the one section and engaging the other said section.

5 8. A wheel comprising two relatively movable members, one a tire member and the other a hub member, and having a cushioning device between them, the hub member comprising two hub-sections, a plurality of spokes, 10 and a rim, one of said hub-sections provided with a central orifice adapted to receive a projection upon the other hub-section, and the

said other section provided with a central projection adapted to pass through said orifice; and a locking device between the first said 15 hub-section and the projection of the other said hub-section; the said spokes being straight-line compression-spokes and arranged in pairs, each pair converging from the opposite hub-sections to the said rim.
